US00D786264S

(12) **United States Design Patent** (10) Patent No.: **US D786,264 S**
Lin et al. (45) Date of Patent: ** May 9, 2017

(54) **DATA ACCESSING DEVICE**

(71) Applicant: **Kingston Digital, Inc.**, Fountain Valley, CA (US)

(72) Inventors: **Yi-Ting Lin**, Hsinchu (TW); **Yu-kuo Huang**, Hsinchu (TW); **Peter Leekuo Chou**, Fountain Valley, CA (US)

(73) Assignee: **Kingston Digital, Inc.**, Fountain Valley, CA (US)

(**) Term: **15 Years**

(21) Appl. No.: **29/559,924**

(22) Filed: **Mar. 31, 2016**

(51) LOC (10) Cl. **14-03**

(52) U.S. Cl.

USPC **D14/480.1**

(58) **Field of Classification Search**

USPC D14/480.1-480.7, 435.1, 411, 433, 436, D14/484.1, 137, 155, 203.1-203.8, 240, D14/242; D13/133, 154

CPC H05K 5/0278; G06K 19/07732

(57) **CLAIM**

The ornamental design for a data accessing device, as shown and described.

DESCRIPTION

FIG. 1 is a perspective view of a data accessing device showing the claimed design;

FIG. 2 is another perspective view of FIG. 1;

FIG. 3 is a front elevational view of FIG. 1;

FIG. 4 is a rear elevational view of FIG. 1;

FIG. 5 is a left side elevational view of FIG. 1;

FIG. 6 is a right side elevational view of FIG. 1;

FIG. 7 is a top plan view of FIG. 1; and,

FIG. 8 is a bottom plan view of FIG. 1.

The broken lines in the drawings represent unclaimed subject matter and form no part of the claim.
